US0D1045521S

(12) **United States Design Patent** (10) Patent No.: **US D1,045,521 S**
(45) Date of Patent: ** Oct. 8, 2024

(54) **CONFECTIONERY DISPENSER**

(71) Applicant: **MARS, INCORPORATED**, McLean, VA (US)

(72) Inventors: **Rory Johnston**, Hampshire (GB); **Steve Waters**, Buckinghamshire (GB); **Matthew Austwick**, Bedford (GB); **Chris MacKintosh**, Weybridge (GB); **Regis Adam**, Bischwiller (FR); **Thibaud Capra**, Niederhausbergen (FR); **Bernhard Huptas**, Hamburg (DE); **Daniel Muscheid**, Munich (DE); **Michael Zeidler**, Munich (DE)

(73) Assignee: **Mars, Incorporated**, McLean, VA (US)

(**) Term: **15 Years**

(21) Appl. No.: **29/839,666**

(22) Filed: **May 23, 2022**

(30) **Foreign Application Priority Data**

Nov. 23, 2021 (EM) 008770580
